UNITED STATES PATENT OFFICE.

HENRY LEITNER, OF LONDON, ENGLAND.

APPARATUS FOR THE CONTROL OF ELECTRIC CIRCUITS.

1,109,536.

Specification of Letters Patent. Patented Sept. 1, 1914.

Application filed May 5, 1913. Serial No. 765,673.

To all whom it may concern:

Be it known that I, HENRY LEITNER, a subject of the King of Great Britain, residing at 7 Prince's street, Westminster, London, England, have invented new and useful Improvements in Apparatus for the Control of Electric Circuits, of which the following is a specification.

My invention relates to apparatus for automatically controlling or regulating electric circuits wherein a dynamo is arranged to charge a battery of accumulators, both the dynamos and the accumulators providing current for the electric lamps, etc., fed by the system, the said apparatus being of the kind wherein the rheostat is designed to introduce resistance into, or withdraw it from, a lighting circuit in order to compensate for variations in the voltage of the accumulators, the said rheostat having a series of resistances included in the field circuit of the dynamo and introduced therein or withdrawn therefrom by the rheostat arm operated by an electro-motor or equivalent device controlled by a contact volt-meter.

The object of my invention is to provide that when the movement of the rheostat arm is reversed in either direction of travel such reversal shall not simultaneously affect all the circuits controlled by the rheostat and to this end I provide that the portion of the rheostat arm which carries the contact or contacts for one set of resistances shall have a certain amount of play relatively to the portion or portions of the arm which carries the contact or contacts for the other set or sets.

To enable my invention to be fully understood I will describe it by reference to the accompanying drawing which shows diagrammatically a general arrangement of a regulator of the type referred to, and in which two sets of resistances are controlled, one of these being in the lamp circuit the voltage of which it is desired to maintain constant, while the other is in the shunt field circuit of the dynamo, into which circuit it introduces or withdraws resistance according as the voltage of the supply circuit tends to rise or fall.

A represents a shunt wound dynamo adapted to supply current to a set of accumulators B through an automatic cut-in and cut-out device C, and to a lamp circuit D through that portion of the regulator which comprises the resistance α and the arm c ,

designed to be moved over the resistance α by the electro-motor d controlled by the volt-meter control e , the mechanical connection between the arm and motor (comprising in this instance a rack c' secured to the arm c and engaged by a pinion c^2 driven by means of a belt c^3 from the motor d). The resistance α is designed to be introduced into, or cut out of, the lamp circuit D by the movement of the arm c when actuated by the electro-motor. The resistance b is in circuit with the shunt field winding of the dynamo, and introduces or cuts out resistance from this circuit by the movement of the subsidiary arm or brush f . The movement of this latter arm f is controlled by the movement of the arm c , but in such a manner that the said arm c can move a certain distance in either direction without moving the arm f . For this purpose the arm c is made with an insulated forked extension g , g' which engages on either side with the arm f , say for example by means of an outwardly projecting pin or projection h . It will be obvious, however, any other suitable arrangement may be made use of for obtaining a like result.

With this arrangement it will be seen that a reverse movement of the arm c can take place in either direction for a certain distance without affecting the arm or brush f . Then if by continued movement of the arm c in contact with the arm or brush f , say, more resistance is inserted in the field circuit of the dynamo, and the E. M. F. reduced, the volt-meter-control e will respond, and will cause the motor d to work in such a direction as to cut out resistance in the lamp circuit resistance α , which operation can be effected without moving the arm f , and thereby a "hunting" action is avoided. It is obvious that more than one subsidiary arm may be controlled in this manner by the arm c , and thereby more than one set of subsidiary resistances, and I do not confine myself to the particular arrangement or application of the invention herein shown, since it will be understood that it is susceptible of many variations.

Claims:

1. In an electric system, the combination with a lamp circuit, a battery of accumulators, a dynamo, a rheostat provided with a plurality of series of resistances, a movable arm adapted to cut certain of said resistances in and out, and an electric motor for

operating said arm, of a part operated by said rheostat arm in both directions, for cutting in and out certain other of said resistances, said part being connected with 5 said arm by means permitting lost motion in both directions whereby when the movement of said arm is reversed in either direction of travel, certain only of said plurality of series of resistances are affected, 10 without immediately affecting others.

2. In an electric system, the combination with a lamp circuit, a battery of accumulators, a dynamo, a rheostat, provided with a plurality of series of resistances, a movable 15 arm adapted to cut certain of said resistances in and out, and an electric motor for operating said arm, of a subsidiary resistance controlling arm for cutting in and out certain other of said resistances, driven by 20 the main arm in both directions, but having a certain amount of play with respect thereto, in both directions of movement of said operating arm.

3. In an electric system, the combination with a lamp circuit, a battery of accumulators, a dynamo, a rheostat, provided with a plurality of series of resistances, a movable 25 arm adapted to cut certain of said resistances in and out, and an electric motor for operating said arm, said rheostat arm be-

ing provided with bifurcated portions, of a subsidiary controlling arm located between said bifurcated portions, and movable thereby in both directions, for controlling certain other of said series of resistances and capable of slight relative movement with respect to said bifurcated portions, in both directions of movement thereof. 35

4. In an electric system, the combination with a lamp circuit, a battery of accumulators, a dynamo, a rheostat comprising a series of resistances in the lamp circuit, a series of resistances in the shunt field winding of the dynamo, and a rheostat arm for cutting in and out the lamp circuit resistance, of a part operatively connected with but movable with respect to the rheostat arm for cutting in and out the resistance in the shunt field winding of the dynamo, a motor for operating the rheostat arm, and a voltmeter control device for said motor, whereby the resistance in the lamp circuit may be changed without immediately altering the resistance in the shunt field winding of the dynamo. 40 45 50
